PIECE-WORK RECORDING MACHINE

Benjamin Cooper, New York, N. Y.

Application October 12, 1938, Serial No. 234,613

8 Claims. (Cl. 101—96)

This invention relates to a piece-work recording machine and more particularly to a machine for recording information according to a pre-arranged code as indicated by perforations in a card or sheet of paper.

In a system wherein perforated cards are used, the practice is to perforate a card according to a pre-arranged code. The perforations, indicating by code such items as style, rate per piece, operations to be performed, etc.

In machines of the mechanical type wherein fingers are used to pick up the perforations, because of the numerous punchings and the wear and tear on the card as it passes through the machine, it has been found necessary heretofore to make the cards of a strong cardboard or equivalent material.

An object of the present invention is to provide an apparatus of the character described which shall be simple and rugged in construction, convenient in use, and which shall enable quick and accurate determination of the data in question.

A still further object being to print a correlation of items upon a ticket to convey information to a worker indicating such items as style, rate per piece, operations to be performed, etc., which go with the work.

A further object is to mechanically move recording members in differential steps by means of a record sheet.

Another object is to provide means for selectively setting the recording means, and to lock the plurality of settings for a recording thereof.

A further object is to provide means for resetting recorder to insure recorder being at normal starting position before again exercising control over same.

A still further object is to provide means for recording information according to a pre-arranged code wherein the card or sheet of paper is so held as to transfer the wear and stress on it to the holding members.

An object of the present invention consists in making a setting device for a recorder dependent upon the insertion of a card or sheet, having a pre-arranged code thereon, and maintaining that record in a holding means and advancing the record past a plurality of feelers or pickup arms, to cause the setting thereof.

Other objects and characteristic features of the invention will appear from the following detailed description of one embodiment thereof, taken in connection with the accompanying drawings wherein identical reference numerals

are applied to the same parts in the several figures, and in which—

Fig. 1 is a side elevational view of the recording machine shown partially in section to illustrate the details of construction;

Fig. 2 is a side elevational view, partially in section, of the card holding and setting assembly shown in an open position;

Fig. 3 is a side elevational view of the recording machine, partially in section, showing the machine in a recording position;

Fig. 4 is an elevational view taken on line 4—4 of Fig. 3;

Fig. 5 is a front elevational view showing part of the structure broken away to illustrate the recording means;

Fig. 6 is a side elevational view of the other side of the machine illustrating the crank and dial setting means; and

Fig. 7 is an exploded view of the card holding assembly.

In the embodiment of the invention herein disclosed there is provided an enclosing frame 10 for the recording mechanism, having a wall 14 so shaped as to cover the top and rear of the machine, bearings 29 being formed in the upper portion of wall 14. Frame 10 has a front wall 15 and side walls 20. Front wall 15 has an opening 41 therein, the lower portion of opening 41 having a sheet holding bed 17 which is an integral part of the front wall 15, the sheet holding bed 17 having an opening 32 therein. In the lower portion of the front wall 15, a bearing 27 is formed. A card setting and holding assembly 11 is mounted in the upper front portion of frame 10, as shown in Figs. 1, 3, 5, and 6.

A shaft 47 is mounted between side walls 20, carrying thereon a recording assembly 16 which consists of type holding cams 42, 43, 44, and 45, Fig. 5, having a type face 63 on the outer face of each. Type carriers 44 and 45 have lever arms 67 and 68, Fig. 3, connected therewith, and type carriers 42 and 43 have geared segments 48 and 49 respectively connected therewith. The lever arms 67 and 68 are normally held in an inoperative position by springs 78 and 79 attached thereto and being connected at their other ends to a cross bar 80, the lever arms 67 and 68 being held against a stop pin 33, as shown in Fig. 1. Attached to the ends of lever arms 67 and 68 by means of pins 69 and 70 are pickup points 75 and 76 respectively.

Gear segments 48 and 49 are engaged by the gears 51 and 52 respectively, the gears 51 and

52 being mounted upon shafts 53 and 54 respectively, said shafts passing through the side wall 20 which acts as a bearing for same, and having mounted on their outer ends dials 55 and 57 respectively. The geared segments 48 and 49 are retained in position by means of setting pawl levers 58 and 59 respectively. The pawl levers 58 and 59 are pivotally mounted on a pin 46 and attached at their other ends to rods 60 and 61. The rods 60 and 61 pass upwardly through the 10 bearings 29 and have at their upper ends push buttons 64 and 65 respectively affixed thereto. Mounted on the rods 60 and 61 between the bearings 29 and push buttons 64 and 65 are springs 62 which normally hold the pawls 58 and 59 engaged with gear segments 48 and 49 respectively.

15 A printing mechanism 18 consists of an electromagnetic coil 21 mounted within frame 10 in any suitable manner, a plunger 25 mounted within coil 21, a shaft 26 mounted between side walls 20 and having a lever 22 mounted thereon which is connected to the plunger 25, and the other end of lever 22 rests against a stop pin 24 when inoperative, and is held there by a spring 23 which is mounted on one side 20 of frame 10, Fig. 1. The spring mounted end of pivot lever 22 has mounted thereon a printing hammer 28 which is in alignment with the opening 32 in the sheet bed 17. A switch means 19 consists of a rod 35 which is mounted in a bearing 27 and 20 restrained from operation by a spring 50 having mounted on its outer end a push button 34. The inner end of rod 35, when operated, engages contact 36 causing it to engage contact 37.

25 Inserted in the printing opening 41 of the main frame 10, and passing over the opening 32 in the sheet bed 17, is a paper 31 and an inked ribbon 30 which passes under the type faces 63 of each of the type carriers 42, 43, 44, and 45, Fig. 5, and the ribbon is held in operative position by a pair of rollers 66—66, Fig. 5.

The card setting and holding assembly 11, mounted in the upper front portion of frame 10, consists of a frame portion 12 which is made up of a front wall 105, a rear wall 106, a bottom 108, and side walls 107—107, Figs. 1 and 3. The rear wall 106 has an elongated slot 103, Figs. 3 and 5, running approximately the perpendicular length of the wall. Extending from the upper portion of front wall 105 is a reset button bracket 83, Figs. 1 and 3. The bracket 83 is an extension of the side wall 107, Fig. 6, and has a face portion 77, Fig. 3. A rod 85 passes through the face 77 of the bracket 83 and through the front wall 105 of the frame 12, Fig. 3. Mounted on the outer end of rod 85 is a resetting button 81, also mounted on the rod 85 is a stop member 86 and spring 84, Figs. 1 and 3, both being positioned between the bracket face 77 and the front wall 105 of frame 12, the stop member 86 being pinned to the rod 85. The inner end of rod 85 engages a leg 99 of a resetting lever 96, Fig. 3, which is pivoted at a point 98 to the frame 12. The leg 99 has a spring 97 attached thereto and said spring is attached at its other end to the frame 12. The lever 96 has another leg 100 which engages the rear face of a rack frame 118, Fig. 1, through an opening 113 in the rear wall 106 of frame 12, as shown in Fig. 1.

70 Mounted loosely through an opening 94 in wall 105, is a rectangular push member 87 which also passes through an opening 114 in wall 106. On the outer end of the member 87 a release and locking button 82 is mounted. On the other end of member 87 a stop pin 90 is mounted, and a

short distance from the end of the member 87, an arm 89 extends downwardly and has a spring 88 attached thereto and which is also attached to wall 105 of the frame 12. Midway of the member 87 a pin 91 is inserted which acts as a stop means preventing the member 87 from being withdrawn from the frame 12. On the upper face of member 87, at a point forward of the stop pin 91, a slot 92 is formed having right angular shoulders 93, Figs. 1 and 3. In operation, the button 82 is pushed inwardly and then upwardly, as shown in Fig. 2, causing the front wall 105 to fit into slot 92 holding the member 87 in an engaged position, Fig. 2.

A card holding assembly 13, Fig. 7, consists of a pinion rack 115, washers 116, holding screws 117, the rack frame 118, a paper guide frame 120, a U-shaped frame 127 and a spring 125. The rack frame 118 is slidably mounted on the outside face of the rear wall 106 of the frame 12, and the pinion rack 115 is slidably mounted on the inside face of the wall 106, both being positioned by the screws 117 which pass through rack 115, the washers 116, the elongated slot 103 of wall 106, and are threaded into the rack frame 118, holding the whole card holding assembly 13 in a slidable engagement with the wall 106 of frame 12. The outer face of rack frame 118 has a toothed rack 119 substantially covering the whole outer face. The lower end of the rack frame 118 has a rod 112 mounted therein, as shown in Fig. 7. The rod 112 passes through the elongated slot 103 of wall 106, as shown in Figs. 3 and 5, and has a spring 111 attached thereto, which is attached at its other end to a fixed rod 110 mounted in the frame 12, as shown in Figs. 3 and 5. Engaging with the pinion rack 115 is a pinion gear 101, Figs. 3 and 5. The pinion gear 101 is mounted on a shaft 102 which passes through the side wall 107 of the frame 12, mounted on the outer end of shaft 102 and keyed thereto is a bell crank lever 104 which is used to turn the gear 101 when moving the pinion rack 115. Fixed to the rack frame 118 is a card guide frame 120, as shown in Fig. 1. The frame 120 has the two side walls 141 and 142 and the bottom 143 engaging the rack frame 118, as shown in Fig. 7. The guide frame 120 has two elongated slots 121 and 122 through its face 140 and two rectangular openings 123 and 124 also through the face 140, Figs. 4 and 7. Mounted on the face 140 is a spring leaf 125. Mounted on the frame 120, Fig. 7, by pivot pins 138 and 139, is a U-shaped frame 127 which consists of two arms 129 and 130 and a base 128, Figs. 4 and 7. The upper end of the arms 129 and 130 receive the pivot pins 138 and 139, the intermediate portion of the arms 129 and 130 have inwardly and downwardly bent prongs 133 and 134 which have points 135 and 136, Fig. 7. The points 135 and 136 fit respectively into the openings 123 and 124 of the frame 120, Fig. 7. The base 128 has an extended portion 131 which, in operation, engages the pickup arms 73 and 74, Fig. 2. The spring 125 is attached to frame 120 and rests at its outer end on the sprong 134, so that it will keep the U-shaped frame 127 in a spring pressed position, as shown in Figs. 1 and 3.

To illustrate the operation of the machine, let it be assumed that the machine is ready for operation as in Fig. 1. The first step is to push the button 82 inwardly against the tension of the spring 88 and allow the slot 92 to align with the wall 105, then allow the shoulder 93 to engage wall 105, this in turn causes the stop pin 90 to

move outwardly to prevent the movement of the card holding means 13 and in turn to cause the end of member 87 to push the frame 127 outwardly as shown in Fig. 2. The frame 127 pushing pickup arms 73 and 74 out of engagement and carrying points 135 and 136 out of position, allows a card to be inserted in the space between the inner side of face 140 and the rack face 119 as shown in Fig. 2. The locking button 82 is then released from engagement with frame 12, the spring 88 returning it to its normal position with stop pin 91 against wall 105. This in turn allows frame 127 to return to its normal position, frame 127 allowing the pickup arms 73 and 74 to fall against the face of this inserted card and also allows the spring pressed points 135 and 136 to engage the face of card, holding it against movement.

The card being set, this device is ready for operation. Let it be assumed that the bell crank 104 is turned clockwise as indicated by arrow in Fig. 6, until it reaches the dotted position against the stop pin 109, as shown in Fig. 6. This will cause the pinion gear 101 to move the pinion rack and card holding assembly downwardly until it reaches a position as shown in Figs. 3 and 5. During the downward movement of the assembly 13, the pickup arm points 75 and 76 pass over the face of the paper 31 until they reach a perforation in the paper which allows them to be spring pressed through this perforation and engage the particular tooth of the rack 119 of frame 118, assuming positions, for example, as shown in Figs. 3 and 4. When the pickup points 75 and 76 have engaged the rack 118 they move downwardly with the rack until the rack reaches the position, as shown in Fig. 3, when the reset lever 96 will engage by means of the end 100, the top of the rack 118 thus locking it in position for the printing operation. The pickup arms 73 and 74, having been carried downwardly by the frame 118, will move the type holding cam levers 67 and 68 downwardly to a position as shown in Figs. 3, 4, and 5. This in turn will cause the type carriers 44 and 45 to be moved in direct relation with levers 67 and 68, as shown in Fig. 3, thus being positioned for a printing operation.

To reset this part of the mechanism, the reset button 81 is pushed inwardly against the tension of spring 84 engaging leg 99 of lever 96 and retracting leg 100 from the top surface of frame 118 which will allow the spring 111, by means of the rod 112 which is attached to the frame 118, to restore the said frame to its normal starting position as shown in Fig. 1. The pickup arms 73 and 74 being released are returned to their normal position, as shown in Fig. 1, by springs 78 and 79.

In this mechanism there are provided a plurality of type carriers two of which, 42 and 43, are shown as being actuated by a dial mechanism. To set these carriers for printing, the dials 56 and 57 are rotated to a desired setting as shown in Fig. 6. The setting of these dials in turn, through their connected gears 51 and 52, and segmental gears 48 and 49, actuate the carriers 42 and 43 with which they are connected. During the setting operation of carriers 42 and 43, it is necessary to press push buttons 64 and 65 downwardly so that they in turn will release the setting pawls 58 and 59. When the carriers 42 and 43 are in position, the push buttons 64 and 65 are released and the setting pawls 58 and 59 are spring pressed into engagement with the segmental gears 48 and 49 retaining the carriers

42 and 43 in a printing position. To reset the type carriers 42 and 43, it is necessary to again press the push buttons 64 and 65 and, by means of the dials 56 and 57, to return them to a zero position.

Assuming that the carriers are in position for printing and a paper 31 has been inserted for printing, as shown in Fig. 3, the switch means 19 is actuated by pressing the switch button 34 closing the contacts 36 and 37 which completes a circuit which may be traced as follows:

From one side of the source of power 40, through the conductor 39, contacts 36 and 37, conductor 38, coil 21, through conductor 55, to the other side of 40.

The electromagnetic coil 21, being actuated, will cause plunger 25 to move downwardly actuating the connected lever 22 causing the printing hammer 28 to be moved quickly against the tension of spring 23 to a printing position against the paper 31, carrying it against the inked ribbon 30 and type faces 63 of type carriers 42, 43, 44, and 45, thus completing a printing operation. The release of switch 19 and subsequent breaking of the circuit allows spring 23 to return the lever 22 to its normal position against the stop pin 24, as shown in Fig. 1.

In this machine, it is quite immaterial whether it be a card or paper or other thin sheet material having perforations therein, as the perforated record is spring pressed between two flat members holding it rigidly for operation; there is little or no dependence upon the strength of the material to either support it in position or to provide for the wear upon it.

The operation of the device having been described, this embodiment of the invention herein disclosed, is merely illustrative and may be modified and departed from in many ways, such as the provision of a power means for rotating shafts 102 and 26, without departing from the spirit and scope of the invention as pointed out in and limited solely by the appendant claims.

What is claimed is:

1. In a machine of the character described, a frame, a horizontal shaft on said frame, a type carrying member mounted for rotation about the axis of said shaft, a holder slidably mounted on said frame for vertical movement, said holder being provided with a ratchet portion, and a member pivoted to said type carrying member and adapted to engage one of the teeth of said ratchet portion, means for slidably moving the holder downwardly, spring means to move the holder upwardly, means to disengage said pivoted member from said ratchet portion, when said holder is in initial position, a second type carrying member mounted for rotation about the axis of said shaft, means to rotate said second type carrier member, and means to print the data of said positioned type carrying members.

2. In a machine of the character described, a rotatably mounted member carrying fixed type against which a record may be printed, a slidably mounted holder provided with a ratchet portion and adapted to receive a perforated card covering the ratchet portion, a member pivoted to the type carrying member and having a portion adapted to project through the perforation in the card to engage one of the teeth in the ratchet portion, means to slidably move the holder in one direction to rotate said type carrying member in one direction, when the pivoted member engages the ratchet portion, a second rotat-

ably mounted member carrying fixed type, means to rotate said second member, means to retain said second member in its rotated position, means to move said second member back to initial position, and means to print the data of said positioned type carrying members.

3. In a machine of the character described, a rotatably mounted member, carrying fixed type against which a record may be printed, a slidably mounted holder provided with a ratchet portion and adapted to receive a perforated card covering the ratchet portion, a member pivoted to the type carrying member and having a portion adapted to project through the perforation in the card to engage one of the teeth in the ratchet portion, means to slidably move the holder in one direction to rotate said type carrying member in one direction, when the pivoted member engages the ratchet portion, means to disengage the pivoted member from said ratchet portion, when said holder is in initial position, a second rotatably mounted member carrying fixed type, means to rotate said second member, means to retain said second member in its rotated position, means to move said second member back to its initial position, and means to print the data of said positioned type carrying members.

4. In a machine of the character described, a rotatably mounted member carrying fixed type against which a record may be printed, a slidably mounted holder provided with a ratchet portion and adapted to receive a perforated card covering the ratchet portion, a member pivoted to the type carrying member and having a portion adapted to project through the perforation in the card to engage one of the teeth in the ratchet portion, means to slidably move the holder in one direction to rotate said type carrying member in one direction, when the pivoted member engages the ratchet portion, and spring means to rotate said type carrying member in an opposite direction, a second rotatably mounted member carrying fixed type, means to rotate said second member, means to retain said second member in its rotated position, means to move said second member back to its initial position, and means to print the data of said positioned type carrying members.

5. A recording device comprising, a type carrier, a movable holder provided with a member having a series of stops, and adapted to receive a perforated card covering said stop member, a member pivoted to said type carrier, having a portion adapted to project through the perforation in said card to engage one of the stops in the stop member, means to move said holder a predetermined distance to move said type carrier a distance dependent upon the position of said perforation in said card, a second type carrier, means to move said second type carrier a predetermined distance, means to hold said second type carrier in the position to which it has been moved, means to return said second type carrier to initial position, and means to print the data of said positioned type carriers.

6. A recording device comprising, a type carrier, a movable holder provided with a member having a series of stops and adapted to receive a perforated card covering said stop member, a member pivoted to said type carrier, having a portion adapted to project through the perforation in said card to engage one of the stops in the stop member, means to move said holder a predetermined distance to move said type carrier a distance dependent upon the position of said perforation in said card, means to retain said holder in its moved position, means to return said holder to its initial position, means to disengage said member from said holder when said holder is in its initial position, a second type carrier, means to move said second type carrier a predetermined distance, means to hold said second type carrier in the position to which it has been moved, means to return said second type carrier to initial position, and means to print the data of said positioned type carriers.

7. A recording device comprising, a type carrier, a movable holder provided with a member having a series of stops and adapted to receive a perforated card covering said stop member, means on said holder to engage said card for preventing relative movement between said card and said holder during movement of said holder, a member pivoted to said type carrier, having a portion adapted to project through the perforation in said card to engage one of the stops in the stop member, means to move said holder a predetermined distance to move said type carrier a distance dependent upon the position of said perforation in said card, a second type carrier, means to move said second type carrier a predetermined distance, means to hold said second type carrier in the position to which it has been moved, means to return said second type carrier to initial position, and means to print the data of said positioned type carriers.

8. A recording device comprising, a type carrier, a movable holder provided with a member having a series of stops and adapted to receive a perforated card covering said stop member, means on said holder to engage said card for preventing relative movement between said card and said holder during movement of said holder, a member pivoted to said type carrier, having a portion adapted to project through the perforation in said card to engage one of the stops in the stop member, means to move said holder a predetermined distance to move said type carrier a distance dependent upon the position of said perforation in said card, means to retain said holder in its moved position, means to return said holder to its initial position, means to disengage said member from said holder when said holder is in its initial position, a second type carrier, means to move said second type carrier a predetermined distance, means to hold said second type carrier in the position to which it has been moved, means to return said second type carrier to initial position, and means to print the data of said positioned type carriers.

BENJAMIN COOPER.
